UNITED STATES PATENT OFFICE

114,461

DESIGN FOR A BOTTLE

Joseph B. Platt, New York, N. Y., assignor to R. H. Macy & Co., Inc., New York, N. Y., a corporation of New York

Application January 20, 1939, Serial No. 82,494

Term of patent 14 years

To all whom it may concern:

Be it known that I, Joseph B. Platt, a citizen of the United States, residing at New York, in the county of New York and State of New York, have invented a new, original, and ornamental Design for a Bottle, of which the following is a specification, reference being had to the accompanying drawing, forming part thereof.

Figure 1 is a side elevational view of the bottle
showing my new design;

Fig. 2 is a similar view turned on an axis of

Fig. 3 is a top plan view;

Fig. 4 is a bottom plan view.

I claim:

The ornamental design for a bottle, as shown.

JOSEPH B. PLATT.
